HOOK FOR SHOWER CURTAINS OR THE LIKE

Heinz Nathanson, New York, N.Y., assignor to Heinz Nathanson Incorporated, New York, N.Y.

Filed Oct. 28, 1971, Ser. No. 193,616

Term of patent 14 years

Int. Cl. D8—08

U.S. Cl. D8—248

FIG. 1 is a front elevation of the hook for shower curtains or the like.

FIG. 2 is a rear elevational view of the hook, and
FIG. 3 is a side elevational view of the hook.

The characteristic feature of the design resides in the "medallion" portion thereof.

I claim:

The ornamental design for a hook for shower curtains or the like, substantially as shown and described.
